DESIGN FOR A FINGER RING

Valentine Linda Fulton, Little Rock, Ark.

Application July 3, 1934, Serial No. 52,451

Term of patent 7 years

To all whom it may concern:

Be it known that I, VALENTINE LINDA FULTON, a citizen of the United States, residing at Little Rock, in the county of Pulaski and State of Arkansas, have invented a new, original, and ornamental Design for a Finger Ring, of which the following is a specification, reference being had to the accompanying drawing, forming part

Figure 1 is a front view;
Fig. 2 is a rear view; and
Fig. 3 is a flattened elevational view slightly in perspective, of a finger ring showing my design.

I claim:

The ornamental design for a finger ring as shown.
In testimony whereof I affix my signature.

In the drawing:

VALENTINE LINDA FULTON.
